Dewey & Le

UNITED STATES PATENT OFFICE.

TIMOTHY STEBINS, OF SAN FRANCISCO, CALIFORNIA.

IMPROVEMENT IN FRICTION-CLUTCHES.

Specification forming part of Letters Patent No. 131,795, dated October 1, 1872.

To all whom it may concern:

Be it known that I, TIMOTHY STEBINS, of city and county of San Francisco, State of California, have invented an Improved Friction-Clutch; and I do hereby declare the following description and accompanying drawing are sufficient to enable any person skilled in the art or science to which it most nearly appertains to make and use my said invention or improvements without further invention or experiment.

My invention relates to an improved friction-clutch, such as are employed for hoisting-pulleys, and for other like purposes, where it is necessary that the pulley shall revolve freely in one direction, and lock itself by the reverse motion immediately upon the power being removed. My friction-clutch consists of a slotted disk, so arranged inside of a peculiar box-pulley that bars can be placed in the slots with one end moving against the inside of the rim. These bars are so constructed and applied that when the disk is revolved in one direction they will move around with it; but when, by accident or otherwise, the power is reversed, the bars will bind against the rim, and serve as a clutch, to hold the disk in place.

In order to more fully illustrate my invention, reference is had to the accompanying drawing forming a part of this specification, in which—

A represents a hollow pulley, having a rim and one side, as shown; and B the shaft upon which it revolves. The side of this pulley is constructed with an interior circular ledge, C, somewhat smaller than the diameter of the inside of the pulley, thus leaving an annular channel, d, between the rim of the ledge and the rim of the pulley A. A circular disk, E, slips down over the shaft B, so as to lie against the face of the ledge C, inside of the pulley, and is keyed firmly to the shaft. This disk is provided with one or more radial slots, f f, which extend from near its hub at g to the outer edge of the disk, as shown. These slots are made wide enough to admit of bars h to lie in them. The outer ends of these bars h are bent at right angles, or otherwise formed so as to provide a projection, i, which lies and moves in the channel d, while their opposite ends bear against the opposite end of the slot. The object of thus fitting the bars is to give a greater amount of surface against the rim

of the pulley for frictional purposes, while the bent ends, fitting in the channel d, steady the bars in their movements. The slots f f are so constructed that when the bars h lie flat against one of their sides a radial line, drawn from the center of the disk to its periphery through the slots, will pass directly through the middle of the bars; and when in this position the disk can be moved around in one direction by revolving the shaft B, the bars moving with it. The slots are wider than the bars, and the sides opposite their straight sides are curved from the inner to the outer end of the slots, thus making them wider at the rim of the disks than at the bottom or end nearest the center. The bottoms of the slots are also made upon the curve of a circle drawn from the center of the shaft, so that when it is attempted to revolve the shaft B backward, or in the reverse direction from that above mentioned, the bars will immediately bind against the rim of the pulley A, and lock the disk in its position.

A cap may be fitted over the open end of the pulley, and thus the entire movement be concealed and protected.

By this means I provide a cheap and effective friction-clutch, which cannot be fouled, and which will prevent many accidents, by locking itself should any of the machinery connected with it give way. It is also serviceable for hoist-ways, and for similar purposes.

Having thus described my invention, what I claim, and desire to secure by Letters Patent, is—

1. The outer shell or pulley A, in combination with the radially-slotted disk E, and brake-bars h, substantially as and for the purpose above described.

2. The pulley A, having one side provided with a ledge, c, so as to form an annular channel, d, in combination with the brake-bars h, having the projection i, substantially as and for the purpose above described.

3. The slots f f, having one straight and one curved side, and a curved bottom, in combination with the brake-bars h, substantially as and for the purpose above described.

In witness that the above-described invention is claimed by me I have hereunto set my hand and seal.

Witnesses: T. STEBINS. [L. S.]
